ATTORNEY

UNITED STATES PATENT OFFICE.

ROBERT H. MORRIS, OF JANESVILLE, WISCONSIN, ASSIGNOR OF ONE-HALF
TO NELS CARLSON, OF SAME PLACE.

HAY ELEVATOR AND CARRIER.

SPECIFICATION forming part of Letters Patent No. 312,151, dated February 10, 1885.

Application filed December 20, 1884. (No model.)

To all whom it may concern:

Be it known that I, ROBERT H. MORRIS, of 5
Janesville, in the county of Rock and State of
Wisconsin, have invented certain new and
useful Improvements in Hay Elevators and
Carriers; and I do hereby declare the follow-
ing to be a full, clear, and exact description
of the invention, such as will enable others
skilled in the art to which it appertains to
make and use the same.

My invention relates to an improvement in
hay elevators and carriers, the object of the
same being to provide improved means for
automatically locking the hoisting-tackle in
elevated adjustment and simultaneously there-
with releasing the carriage, and for simultane-
ously releasing the hoisting-tackle and stop-
ping the carriage.

With these ends in view my invention con-
sists in an eccentric bar or plate pivoted to
the carriage and adapted to engage a grip-le-
ver, said eccentric being positively operated
by a link pivoted thereto and adapted to en-
gage a stationary incline.

My invention further consists in certain
features of construction and combinations of
parts, as will be hereinafter described, and
pointed out in the claims.

In the accompanying drawings, Figure 1 is
a view in side elevation, partly in section, of
a hay elevator and carrier embodying my in-
vention; and Fig. 2 is a sectional view of the
carriage-way, incline, link, and eccentric
through the line *x y* of Fig. 1.

A represents a track or way, on which a car-
riage, B, depending therefrom, is adapted to
move. The carriage B is supported on the
way by suitable wheels, C. The tackle *a* is
provided with a sheave, *b*, adapted to receive
a hoisting-rope, *c*, on its face, with a depend-
ing hook, *D*, for attaching the hay-grapple,
and with an upwardly-extending loop, *d*, for
engaging and receiving the grip-lever, as will
appear hereinafter. A hoisting and operat-
ing rope, *c*, passes over the face of a pulley,
E, journaled near one end of the carriage,
thence about the sheave *b* in the tackle *a*,
thence over a pulley, *F*, journaled near the
opposite end of the carriage. The rope is
provided with knots or other suitable stops,
(not shown,) so that either end may be pre-

vented from freely sliding over the pulleys *E*
and *F*, as desired. Near the central lower
portion of the carriage a grip-lever, *f*, is piv-
otally secured. The lever *f* has its lower end 55
curved toward a stationary projection, *f'*, se-
cured to the lower portion of the carriage,
and is adapted to close in contact with the
projection within the loop *d* of the tackle *a*.
The lever *f* is also provided with an arm, *h*, 60
which extends laterally over the loop *d*. The
upper end of the lever *f* is shaped to engage
the notches on an irregular-shaped eccentric,
I, and thereby lock said eccentric against
movement, and in turn be locked by the ee- 65
centric against movement, in the manner and
for the purposes, as will hereinafter appear.
The eccentric *I* is pivoted to the carriage
above and to one side of the pivotal point of
the lever *f*, and preferably on a vertical line 70
passing through the center of the tackle. The
said eccentric is provided with two shoulders
or notches, *i* and *j*, adapted to engage the
end of the lever *f* when the latter is in open
and closed adjustment, respectively. A link, 75
K, is pivotally secured at its lower end to the
eccentric *I* at a point, *k*, located about half-
way between the pivotal point of the eccen-
tric and one end thereof. The link *K* passes
upwardly through a slot, *L*, in the carriage, 80
and is provided at its upper end with a later-
ally-extending lug or lugs, *l*, which latter are
adapted to engage an inclined groove or in-
clined grooves, *m*. The groove or grooves *m*
are formed in the side or sides of a station- 85
ary block, *M*, secured to the under side of the
carriage-way *A*, and consist of an incline in
the form of an open inverted *C*.

In the position represented in Fig. 1, full
lines, the tackle is supposed to be attached to 90
a fork-load of hay, and the same is being ele-
vated. The carriage is now held against mo-
tion on the way by means of the link *K*, which
is prevented from being depressed as long as
the notch *i* on the eccentric rests in contact 95
with the end of the lever *f*, and because of the
downward direction of the grooves with which
the upper end of the link is in contact the
carriage cannot be moved without depressing
the said link. As the tackle is elevated the 100
upper end of the loop *d* passes between the
lower end of the lever *f* and the stationary

projection f' , and strikes against the end of the arm h , lifting it upwardly, and thereby closing the lower end of the grip-lever into contact with the projection f' within the loop.

5 This action of the grip-lever sets free the eccentric, allows the link to move down the incline, and the carriage being now free to move will respond to the pull on the hoisting-rope, force the link down the incline, rotate the eccentric into the position represented in dotted lines, Fig. 1, and thereby lock the grip-lever in closed adjustment, as shown, the upper end of the lever f engaging the notch j on the eccentric. The carriage is now moved on the 10 way without liability of releasing the load until the upper end of the link K comes in contact with a second incline over the point where it is desired to deposit the load. The link, as the carriage moves on, will be drawn 15 up this second incline, unlock the upper end of the grip-lever from the eccentric, release the tackle with its load, and stop the carriage, since the moment the lever f releases the tackle its upper end engages the notch i on the 20 eccentric and prevents the link from further motion down the incline. The return of the carriage for another load is a repetition of the 25 operation just explained.

One of the several advantages of my present invention consists in the positive action 30 of the locking device, by which the annoyance often caused by the clogging of gravity devices is entirely avoided. Furthermore, the arrangement of the link, incline, and eccentric is such that the carriage is not brought to 35 an abrupt stop, and the several parts are saved from sudden shocks and damage.

It is evident that slight changes may be made in the form and construction of the several parts without departing from the spirit 40 and scope of my invention—as, for example, the eccentric might be of many shapes different from that shown and yet perform the same function; hence I do not wish to limit myself 45 strictly to the construction herein set forth; but,

Having fully described my invention, what I claim as new, and desire to secure by Letters Patent, is—

50 1. In a hay elevator and carrier, the combination, with a grip-lever pivoted to a carriage and a projection rigidly secured to said carriage, of an eccentric bar or plate having two shoulders thereon, with which the lever engages, a stationary incline, and a link connected to the eccentric and adapted to engage

the incline, thereby locking the lever in open adjustment and stopping the carriage, substantially as set forth.

2. In a hay elevator and carrier, the combination, with a carriage, a projection secured thereto, and a grip-lever pivoted to a carriage, and adapted to be closed by the action of a movable tackle, of an eccentric bar or plate having two shoulders thereon, adapted to engage the lever and respectively hold the latter in closed and open adjustment, a stationary incline, and a link pivotally secured to the eccentric and adapted to engage the incline, whereby the lever is locked in closed adjustment and the carriage released, substantially as set forth.

3. In a hay elevator and carrier, the combination, with a carriage, a grip-lever pivoted thereto, and an eccentric bar or plate having shoulders thereon, which latter engage the upper end of the lever, of a sliding link connected with the eccentric, and adapted to engage an incline secured to the carriage-way, whereby the reciprocating motion of the carriage imparts a positive rocking motion to the eccentric, substantially as set forth.

4. In a hay elevator and carrier, the combination, with a grip-lever adapted to be opened and closed by the downward and upward pressure of a movable tackle, of a notched or shouldered rock bar or plate located above the lever and adapted to engage the upper end of said lever, a stationary incline, and a link pivotally secured to the rock bar or plate near one end of the latter, the link being adapted to engage the said incline, and thereby operate the rock bar or plate, substantially as set forth.

5. In a hay elevator and carrier, the combination, with a carriage and a rock bar or plate located near the upper end of a grip-lever, and provided with two notches or shoulders on one side for engaging the end of the lever, the plate and lever being pivotally secured to the carriage, of an operating-link pivoted to the rock-bar near one end of the latter, said link being held against lateral motion by passing through a slot in the carriage and caused to move vertically in the slot by an incline, substantially as set forth.

In testimony whereof I have signed this specification in the presence of two subscribing witnesses.

ROBERT H. MORRIS.
